CLAIM

The ornamental design for a shopping list attachment, as shown and described.

DESCRIPTION

FIG. 1 is a front perspective view of one embodiment of a shopping list attachment in the open position showing the new design;

FIG. 2 is a rear perspective view thereof;

FIG. 3 is a front view thereof;

FIG. 4 is a rear view thereof;

FIG. 5 is a side view thereof;

FIG. 6 is another side view thereof;

FIG. 7 is a top view thereof;

FIG. 8 is a bottom view thereof;

FIG. 9 is a front perspective view of another embodiment of a shopping list attachment in the open position showing the new design;

FIG. 10 is a rear perspective view thereof;

FIG. 11 is a front view thereof;

FIG. 12 is a rear view thereof;

FIG. 13 is a side view thereof;

FIG. 14 is another side view thereof;

FIG. 15 is a top view thereof; and,

FIG. 16 is a bottom view thereof.

The broken lines show portions of the shopping list attachment which form no part of the claimed design. The shade lines in the Figures show contour and not surface ornamentation.

1 Claim, 12 Drawing Sheets
